UNITED STATES PATENT OFFICE

LE ROI E. HUTCHINGS, OF BUFFALO, NEW YORK, ASSIGNOR, BY MESNE ASSIGNMENTS,
TO REMINGTON RAND INC., OF NEW YORK, N. Y., A CORPORATION OF DELAWARE

FILING DEVICE

Application filed May 19, 1926. Serial No. 110,165.

This invention relates to filing devices and has reference more particularly to filing devices in which pockets are supported in a tray or container on a series of substantially 5 horizontally positioned bars.

Certain filing devices have been proposed in which a continuous sheet of material is supported in the form of loops or folds on horizontal bars so as to form a series of pockets for the reception of record data or cards. 10 These devices had the disadvantage that when it was desired to insert reference data requiring a new pocket or index label at any point in the system, it was necessary to shift 15 the entire mass of reference data on one side of the pocket data to be inserted. This has been a disadvantage and requires considerable excess time and labor in filing and the system was therefore not as flexible as 20 desired.

An object of this invention is to provide a device of the class described in which each pocket is removably positioned on its support bar so that old or new pockets of data may be 25 taken out or inserted very easily; also to provide removable support bars which can be conveniently removed when a pocket is removed; and also to improve the construction of file devices in other respects hereinafter 30 specified and claimed. Reference is to be had to the accompanying drawings forming a part of the specification in which:

Fig. 1 is a perspective view of my improved 35 file box or filing device.

Fig. 2 is a fragmentary plan view of one end of the filing device.

Fig. 3 is a transverse sectional view 40 through the filing device.

Fig. 4 is a longitudinal, sectional, fragmentary elevation through the filing device.

Fig. 5 is a perspective view of one of the 45 removable pockets.

Fig. 6 is a transverse sectional view 50 through a filing device showing one of the removable support bars.

Figs. 7, 8 and 9 are transverse sectional views taken through a support bar on lines 55 7-7, 8-8 and 9-9 respectively of Fig. 3.

Fig. 10 is a transverse, sectional view 60

through the elements of a support bar showing the same in position for assembly.

Fig. 11 is a perspective view of one of the label holders on a supporting element.

Fig. 12 is a perspective view of one of the 55 removable support bars.

Referring to the drawings by numerals, 15 indicates a container or box which may be constructed of wood, metal or any other suitable material, said box having bottom 16, side 60 walls 17 and end walls 18 and 27. The walls of the container 15 are lined with a lining 19 so that an air space 20 is provided between the outer walls and said lining, this air space forming a certain amount of protection 65 against fire when the container 15 is provided with a fireproof cover not shown. The air space 20 may be filled with any other desired insulator such as asbestos, mineral wool, etc.

A pair of longitudinal slide bars 21 and 22 70 are provided at one end with screw threads adapted to receive inner nuts 23 and outer nuts 24, the threaded end of said bars passing through the end wall 18, said wall being rigidly secured between the nuts 23 and 24 so 75 that the bars 21 and 22 are supported at one end near the top of the container 15. The opposite ends of bars 21 and 22 are received in slots 25 and 26 respectively formed in the opposite end 27 of the container 15, so that 80 said bars may be flexed upwardly thus causing their ends to extend above end wall 27 for the purpose of removing any number of support bars 28 to be more fully described.

Each of these support bars 28 is provided 85 at its ends with loops 29 and 30, said loops being adapted to be received by the slide bars 21 and 22, thus slidably supporting the support bars 28 transversely of the container 15. The loop 29 is provided with an opening 31 and a square shoulder 32, while the loop 30 is provided with a similar opening 33 and angular shoulder 34. This arrangement of shoulders 32 and 34 is provided (Fig. 6) so as to permit one or more of the support bars 28 to be removed by swinging one end upwardly about the slide bar 21 as a pivot, the bar 22 passing through the opening 33, and then removing loop 29 from bar 21 by allowing said bar 21 to pass through opening 31. 100

- Each of the bars 21 and 22 has a series of spaced notches 35, formed on their upper surfaces adapted to receive the upper portion of loops 29 and 30, these notches being arranged in pairs or in aligned relation on the two slide bars 21 and 22 so that when a support bar 28 is supported in corresponding notches, the position of said support bar is substantially transversely to the container 15. In the preferred form of my invention I provide a plurality of folded pockets or receptacles 36 made preferably of a flexible material such as cardboard, heavy paper, cloth, or the like. The upper edge of each fold of the receptacle 36 is provided with a downwardly folded flap 37 adapted to extend over one of the support bars 28 so that one flap 37 engages one support bar in the container 15 while the opposite flap engages an adjacent support bar. In a series of pockets 36, one flap 37 will be on top of a similar flap on the adjacent pocket as clearly shown in Fig. 10. In order to clamp the pockets or folds 36 and flaps 37 a U-shaped clamping member 38 is provided with lower rounded edges 39, the legs of said clamping member 38 being adapted to spring apart so that said flaps and pockets are resiliently clamped between the legs of said U-shaped clamping member 38 in clamped position. Openings 40 are formed in support bars 28 and openings 41 are formed in flaps 37 so that openings 41 register with openings 40. Inwardly pressed lugs or locking projections 42 are formed in the legs of the clamping member 38, these flanges being adapted to enter into the openings 41 and 40, thus yieldingly locking the clamping member 38 in clamping position as shown in Fig. 8.
- 40 Thus record data or cards 43 may be inserted in the pockets 36 supported on support bars 28, and in order to distinguish between these pockets a label holder 44 is removably attached to each bar 28. This label holder 44 has two folds preferably of a transparent material such as celluloid, so that a label 46 may be removably placed between the folds of the label holder and so that index data on said label may be visible through the transparent folds of label holder 44. Label holder 44 is preferably placed at an angle to the vertical as shown in Fig. 9 so as to be readily visible to the user of the filing device, and is secured to a label-holder bar 44^a as by rivets 45. This label holder 44 extends through an opening 47 in the clamping member 38 so as to be removably secured in said opening by the ends of bar 44^a engaging said clamping member 38. The ends of the clamping member 38 (Fig. 3) extend into and partly cover the openings 31 and 33 so as to normally form a lock to prevent the vertical displacement of the support bar 28. When said clamping members 38 are in assembled position, the support bars 28 and pockets 36 may still be

removed from the container 15 by flexing the slide bars 21 and 22 upwardly and moving the support bars 28 longitudinally along said slide bars past the end 27 of the container 15.

In using the device the separate and removable pockets 36 are arranged between the support bars 28 with the flaps 37 extending over adjacent support bars 28. A clamping member 38 is then moved downwardly over flaps 37 on each bar until projections 42 snap into locked position registering with openings 41 and 40. The record matter can then be inserted into the desired pockets 36, the contents of said pockets being indicated by labels 46. When it is desired to remove a number of pockets 36, the slide bars 21 and 22 may be flexed upwardly so that their outer ends are disengaged from slots 25 and 26 whereupon the support bars 28 may be moved longitudinally along the slide bars 21 and 22 until the desired number of pockets 36 move past the container end 27. When it is desired to remove or insert a single pocket, one of the clamping members 38 is moved upwardly out of clamped position, after which a new pocket may be inserted by the addition of another support bar 28 as shown in Fig. 6 and another clamping member 38, and vice versa when the pocket is to be removed.

I would state in conclusion that while the examples illustrated and described constitute a practical embodiment of my invention, I do not limit myself precisely to these details, since manifestly said examples can be considerably varied without departing from the spirit of the invention as defined in the appended claims.

I claim as my invention:

1. In a filing device a series of support bars, means for slidably supporting said bars in a substantially horizontal plane, and a series of independent pockets for reference matter, and means for removably attaching said pockets to said support bars.

2. In a filing device, a series of support bars, means for supporting said bars in a substantially horizontal position, a series of pockets for reference matter, and clamping means adapted to removably attach said pockets to said support bars.

3. In a filing device, a plurality of support bars, means for supporting said bars in a substantially horizontal position, a strip of material formed to provide a pocket having folded portions at the ends, and means for removably attaching said folded portions to said support bars so that said pocket is adapted for the reception of reference matter.

4. In a filing device, a plurality of slide bars, a series of support bars slidably supported by said slide bars in a substantially horizontal plane, a plurality of pockets for the reception of reference matter, and means detachably connecting said pockets on said support bars along the upper edges of said

- pockets, said slide bars having notches for engaging said support bars so as to maintain said support bars in spaced relation.
5. In a filing device, a series of support bars arranged in a substantially horizontal position, a series of folded pockets for reference matter, and a clamping member having resilient legs adapted to clamp the folds of said pockets to each of said support bars.
10. In a filing device, a series of support bars arranged in a substantially horizontal position, a series of folded pockets for reference matter, a clamping member having resilient legs adapted to clamp the folds of said pockets to each of said support bars, and means associated with said clamping member for locking said clamping member in clamping position.
15. In a filing device, a plurality of slide bars, a series of support bars, each support bar having an open loop at each end adapted to slidably and detachably engage said slide bars, and a series of pockets for reference matter having associated means detachably connecting said pockets to said support bars along the upper edges of said pockets.
20. In a filing device, a plurality of slide bars, a series of support bars, each support bar having an open loop at each end adapted to slidably and detachably engage said slide bars, a series of pockets, a plurality of clamping members adapted to detachably secure said clamping members also serving to prevent the transverse removal of said support bars from said slide bars.
25. In a filing device, a series of support bars, means for supporting said bars in a substantially horizontal position, a series of pockets for reference matter having portions engaging said support bars, an index holder, and means detachably securing said pockets and index holder on said support bars.
30. In a filing device, a series of support bars, means for supporting said bars in a substantially horizontal position, a series of pockets for reference matter, means for detachably securing said pockets to said support bars, and index label means detachably associated with said securing means of a support bar.
35. In a filing device, a series of support bars, means for supporting said bars in a substantially horizontal position, a series of pockets for reference matter, clamping members detachably securing said pockets to said support bars, and index label means detachably secured to a support bar by one of said clamping members.
40. In a filing device, a plurality of slide bars, a series of support bars having slotted portions to receive said slide bars for slidably and detachably mounting said support bars independently on said slide bars, and pocket-securing means detachably mounted on each support bar formed for preventing
45. In a filing device, a series of support bars, means for supporting said bars in a substantially horizontal position for relative sliding movement, a series of independent pocket members having fold portions for engagement with said support bars, and means for detachably locking said fold portions on said support bars.
50. In a filing device, a plurality of support bars having slotted openings, means received in said slotted openings for slidably and detachably mounting said bars independently, and means movably mounted on each bar for preventing detachment of said bar from said means in one position.
55. In a filing device, a series of support bars, means for supporting said bars in a substantially horizontal position, a series of pockets for reference matter, clamping members detachably securing said pockets to said support bars, and index label means detachably secured to a support bar by one of said clamping members.
60. In a filing device, a series of support bars, means for supporting said bars in a substantially horizontal position, a series of pockets for reference matter, clamping members detachably securing said pockets to said support bars, and index label means detachably secured to a support bar by one of said clamping members.
65. In a filing device, a series of support bars, means for supporting said bars in a substantially horizontal position, a series of pockets for reference matter, clamping members detachably securing said pockets to said support bars, and index label means detachably secured to a support bar by one of said clamping members.
70. In a filing device, a series of support bars, means for supporting said bars in a substantially horizontal position for relative sliding movement, a series of independent pocket members having fold portions for engagement with said support bars, and means for detachably locking said fold portions on said support bars.
75. In a filing device, a plurality of support bars having slotted openings, means received in said slotted openings for slidably and detachably mounting said bars independently, and means movably mounted on each bar for preventing detachment of said bar from said means in one position.
80. In a filing device, a plurality of support bars having slotted openings, means received in said slotted openings for slidably and detachably mounting said bars independently, and means movably mounted on each bar for preventing detachment of said bar from said means in one position.
